(57) CLAIM

The ornamental design for a refuse cart, as shown and described.

DESCRIPTION

FIG. 1 is a perspective view of a refuse cart showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines shown in the figures are included for the purpose of illustrating portions of the refuse cart and do not form part of the design.
